US00D797546S

(12) **United States Design Patent** (10) **Patent No.:** **US D797,546 S**
(45) **Date of Patent:** **** Sep. 19, 2017**

(54) **DEVICE FOR APPLYING PROTECTIVE COVER TO PHONE**

(71) Applicant: **Zeikos Inc.**, Edison, NJ (US)

(72) Inventor: **Jack Saideh**, Edison, NJ (US)

(73) Assignee: **Zeikos Inc.**, Edison, NJ (US)

(**) Term: **15 Years**

(21) Appl. No.: **29/557,604**

(22) Filed: **Mar. 10, 2016**

(51) LOC (10) Cl. **08-05**

(52) U.S. Cl.

USPC **D8/354**

(58) **Field of Classification Search**

USPC D8/354; D6/540, 553, 567; 455/575.8;
D14/253; 156/249

CPC H05K 13/00; H05K 13/0015
